UNITED STATES PATENT OFFICE.

BENNETT J. CLENDENEN, OF ESKDALE, WEST VIRGINIA.

TAMPING BAR AND NEEDLE.

1,278,594.

Specification of Letters Patent. Patented Sept. 10, 1918.

Application filed October 31, 1917. Serial No. 199,530.

To all whom it may concern:

Be it known that I, BENNETT J. CLENDENEN, a citizen of the United States, residing at Eskdale, in the county of Kanawha 5 and State of West Virginia, have invented a new and useful Tamping Bar and Needle, of which the following is a specification.

The device forming the subject matter of this application is a tamping bar, adapted to 10 be used in mines.

The tamping bar herein disclosed possesses advantages over the old style bar now in use, in that the needle will always operate at approximately the center of the blast hole in 15 stead of operating close to the wall of the hole.

Another object of the invention is to provide novel means whereby the needle is held on the bar in such a way that it can be re- 20 moved readily by a slight tap.

It is within the province of the disclosure to improve generally and to enhance the utility of devices of that type to which the present invention appertains.

25 With the above and other objects in view which will appear as the description proceeds, the invention resides in the combination and arrangement of parts and in the details of construction hereinafter described 30 and claimed, it being understood that changes in the precise embodiment of the invention herein disclosed, can be made within the scope of what is claimed, without departing from the spirit of the invention.

35 In the accompanying drawings:—

Figures 1 and 2 are side elevations wherein the device is viewed from different points;

Fig. 3 is an end elevation, the needle being omitted;

40 Fig. 4 is a cross section on the line 4—4 of Fig. 1;

Fig. 5 is a cross section on the line 5—5 of Fig. 1.

The device forming the subject matter of 45 this application preferably is made of metal throughout and includes a bar 1 provided at one end with a tubular socket 2, the bar 1 including a broadened shank 3 merging into the socket 2. The socket 2 has a longitudinal 50 bore 4 communicating with a longitudinal groove 5 fashioned in the shank 3, the groove

5 running out to nothing upon the bar 1. At its opposite end, the bar 1 is supplied with a laterally extended, plate-like foot 6 having an opening 7. The foot 6 is offset, circumferentially of the bar 1, from the socket 2, so that the opening 7 is not in axial alignment with the bore 4 of the socket 2. 55

The numeral 8 denotes a needle having a head 9 at one end and a point 10 at the other 60 end. The needle 8 is thrust through the bore 4 of the socket 2 and passes along the groove 5. By this operation, the point 10 of the needle is not directed into the opening 7 in the foot 6, but strikes the foot 6 at one side 65 of the opening 7 and close thereto. The point 10 of the needle may then be sprung slightly, to enter the opening 7 in the foot 6 and, by this operation, the point of the needle will be frictionally held in the opening 7, it being possible to back out or loosen 70 the needle by striking the projecting extremity of the point 10 against an object.

Let it be supposed that an approximately horizontal blast hole has been made. Then 75 it is to be observed that in tamping such a hole with an ordinary needle, the tamping almost invariably takes place below the geometric center of the hole, which is an undesirable consideration. In the present instance the tamping will take place in the axis of the hole, or very close thereto, because the point 10 of the needle 8 passes through the opening 7 in the foot 6 which, being received in the hole, serves as a guide 80 for the needle. 85

Having thus described the invention, what is claimed is:—

1. In a device of the class described, a bar provided at one end with a socket, and 90 equipped at its other end with a lateral foot, the foot having an opening; and a needle mounted in the socket, the needle having a point received in the opening of the foot.

2. A device of the class described comprising a bar provided at one end with a socket and supplied at its other end with a lateral foot, the foot having an opening, the opening being disposed out of coaxial alignment with respect to the bore of the socket; and a 100 needle in the socket, the needle including a point engaging the foot at one side of the

opening in the foot, and adapted to be sprung into and advanced through the opening in the foot, to engage the foot, within the contour of the opening, with a frictional hold.

In testimony that I claim the foregoing

as my own, I have hereto affixed my signature in the presence of two witnesses.

BENNETT J. CLENDENEN.
